WILLIAM THOMAS MULLIN, OF PORT ALBERNI, BRITISH COLUMBIA, CANADA.

FILE-HOLDING DEVICE.

1,323,899.

Specification of Letters Patent.

Patented Dec. 2, 1919.

Application filed February 15, 1919. Serial No. 277,356.

To all whom it may concern:

Be it known that I, WILLIAM THOMAS MULLIN, a subject of the King of Great Britain, and a resident of Port Alberni, in the Province of British Columbia, Canada, have invented certain new and useful Improvements in File-Holding Devices, of which the following is a specification.

My invention relates to improvements in file holding devices, and the object of my invention is to devise a simple and inexpensive means adapted to be placed on the point of a file and provide a smooth grip for the fingers other than the file itself, thus preventing the fingers from the soreness which results from gripping the point of the file by the fingers when much filing has to be done.

I attain this object by the construction illustrated in the accompanying drawings in which—

Figure 1 is a side view of my device.

Fig. 2 is a perspective view.

Fig. 3 is a view illustrating the practical application of the invention.

Similar figures of reference indicate similar parts throughout the several views.

1 indicates a jaw member having a slot 2 and a pin extension 3, which extension 30 passes centrally through the shank 4 of a smooth gripping member 5, the pin being riveted over at 6, as shown in Fig. 1, so that the jaw 1 and grip 5 are connected together swivel-fashion. 7 indicates a file and 8 the handle thereof, while 9 indicates a set screw for securing jaw 1 to the file. The slot 2 is made parallel for flat files, but on one side a V-shaped slot 10 is provided so that taper files may be held with equal facility. In order to prevent the point of the screw from wearing out through repeated turning on the rough surface of the files, which are much harder than the screw, a plate 11 is fitted loosely in the underside of the upper 40 part of the jaw 1 and normally flush with the same, as shown in Fig. 2, so that the point of the screw will not come in contact

with the file but will press the plate down thereon to grip the file, and, to maintain the plate against lateral displacement, its ends 50 are turned upwardly as at 12 and 13.

The manner in which the device is used will be readily seen, on referring to Figs. 1 and 3. The point of the file is placed in the jaw slot and the set screw 9 is screwed down 55 on to plate 11 to secure the file in place, after which the point of the file may be guided on the work by gripping the smooth part 5, which, being capable of rotation, enables the file to be moved with great flexibility of 60 action.

From the foregoing it will be seen that I have provided a simple device which enables the point of a file to be gripped by the fingers so that finger soreness will not result 65 although a considerable amount of filing is done.

What I claim as my invention is:

1. A file holding device comprising, a member adapted for attachment to the end 70 of a file opposite the handle end provided with a swivel extension forming a smooth finger grip.

2. A file holding device comprising, a jaw member adapted to receive the end of a 75 file opposite the handle end provided with a swivel extension forming a smooth finger grip, a set screw for securing the jaw member to the file, and a plate interposed between the point of said screw and the file 80 surface.

3. A file holding device comprising, a jaw member adapted to receive the end of a file opposite the handle end provided with a swivel extension forming a smooth finger 85 grip, a set screw for securing the jaw member to the file, and a depressible plate interposed between the point of said screw and the file surface, the ends of said plate being upturned whereby its movement laterally 90 is prevented.

Dated at Port Alberni, B. C., this 17th day of January, 1919.

WILLIAM THOMAS MULLIN.
